ATTORNEY.

UNITED STATES PATENT OFFICE

BEN J. CHROMY, OF HOPKINS, MINNESOTA, ASSIGNOR TO WIRED RADIO, INC., OF NEW YORK, N. Y., A CORPORATION OF DELAWARE

ELECTRICAL TRANSFORMER

Original application filed May 23, 1929, Serial No. 365,534. Divided and this application filed July 12, 1930. Serial No. 467,804.

My invention relates broadly to electrical apparatus and more specifically to a transformer and control system operated thereby.

This application is a division of my application Serial No. 365,534 filed May 23, 1929 for electrical appliances.

One of the objects of my invention is to provide a construction of transformer including primary and secondary windings and 10 an auxiliary winding where the auxiliary winding consists of a bimetallic strip capable of expansion and contraction for controlling a switching circuit according to the current induced therein from the primary winding.

15 Another object of my invention is to provide a transformer system having means for automatically controlling the output thereof in proportion to the induced current.

A further object of my invention is to provide 20 a transformer system including thermostatic control means for controlling the output thereof.

Other and further objects of my invention relate to the automatically controllable transformer construction described more fully in 25 the specification hereinafter following by reference to the accompanying drawing which diagrammatically illustrates the transformer system of my invention.

30 The transformer system of my invention has been illustrated in connection with a glow discharge device of the type employed in electric signs for advertising or other purposes and is caused to flash or flicker in accordance with a predetermined pattern to produce certain desirable and attractive effects.

An electric circuit interrupting mechanism is employed in conjunction with the glow 40 discharge device to connect certain electrodes associated with the device into circuit at predetermined intervals whereby sections of the device are periodically energized and de-energized. Through the use of this invention a 45 dark spot or portion may be caused to "travel" along the glow discharge device whereby a moving effect may be produced in the illuminated sign. Other effects in which multi-colored glow discharge devices of the 50 intermittently illuminated variety are em-

ployed may be produced by using, for example, a plurality of transparent tubes each filled with a different gas or gases, such as neon, argon, helium, nitrogen, krypton, etc. Gases to which small quantities of readily 55 volatile materials, such as mercury, sodium, potassium, lithium, etc., have been added may also be employed in the glow discharge display devices made in accordance with this invention to produce different pleasing and 60 attractive effects.

While I have shown the transformer system of my invention in association with a particular arrangement of glow discharge circuit, it will be understood that any form 65 of load circuit may be employed and that the particular load shown is for illustrative purposes only.

Referring to the drawing a glow discharge tube 37 having electrodes 37a, 37b, 37c, 37d, 70 37e, etc., has been illustrated as energized through the operation of the transformer 38 and the source connected to winding 40.

The transformer 38 which embodies my invention has a primary winding 40, secondary 75 winding 39 and auxiliary secondary winding 42. The winding 42 consists of a bimetallic strip member having the ends thereof interconnected and carrying an extended contactor 43 which sweep over rows of electrical 80 contacts constituting a switching mechanism.

The switching mechanism including the short circuited bimetallic coil 42 which is coupled magnetically to the primary 40 is provided with an insulated contact supporting member 42a which moves the contactor 43 into or out of engagement with any pair of a plurality of radially aligned contacts whereby different sections of the glow discharge tube 37 are energized 90 from selected taps on the secondary winding 39. The normal position for the contactor is in alignment with contact 46 whereupon the relay winding 44 is deenergized and the primary circuit from source 41 remains closed. 95 As the primary 40 of the transformer 38 is energized by the source 41, an electromotive force is induced into the short circuited bimetallic coil 42. The coil 42 due to thermal 100 expansion moves the contactor 43 into suc-

sive engagement with the contacts 46, 47, 50, 48 and 49 and circuits established between the main electrode 37a with the electrodes 37e, 37d, 37c and 37b successively. The portion 5 of the tube 37 between the electrodes 37a and 37e is then caused to glow. The unit or auxiliary secondary 42 continues to expand and move the contactor 43 which is insulated from the unit 42, over successive pairs of 10 contacts and cause different portions of the tube 37 to glow until the circuit between the contact 49 is established whereupon the circuit of the relay 44 is energized by the source 45 and the primary circuit of the transformer 15 38 is opened. Since the transformer 38 is not energized the unit 42 is permitted to cool and return to its original position preparatory for a repeat operation. The relay 44 is preferably a time delay relay which leaves the 20 circuit of the primary 40 de-energized long enough to permit the unit 42 to return to its original position.

That is to say, the relay device 44 has a 25 relatively long time constant and when contactor 43 moves to a position, due to thermal expansion of the thermally responsive strip 42, in which contacts 49 are bridged, the circuit from battery 45 is completed through the winding of relay 44 and after being 30 closed for a sufficient length of time develops sufficient magnetic pull to act upon solenoid 44b against the action of spring 44a for opening contacts 41a and interrupting the circuit from source 41 to primary winding 40. This 35 annuls the magnetic field from primary winding 40 acting upon the secondary winding formed by thermally responsive strip 42 and permits strip 42 to contract thereby moving contactor 43 counter-clockwise to its initial 40 position in shunt with contacts 46. During the restoration of the contactor 43 to its original position, primary winding 40 is de-energized due to the time constant of the relay 44. However, relay 44 loses its magnetic 45 properties after a predetermined time period and spring 44a operates to close the primary circuit by shifting the contact device which shunts the contacts 41a. The circuit is now prepared for a repeat operation as 50 thermal currents will again be established in thermally responsive strip 42 due to induction from primary winding 40. I may employ various types of delayed action relays at the position 44 in the circuit as set forth 55 for example in British Patent 167,468 accepted September 7, 1922; German Patent 440,892, dated April 23, 1925 and United States Patent 1,550,155, dated August 18, 1925. A spring 42a attached to the unit 42 60 insures rapid and certain return of the movable end of the unit 42 to its pre-energized position as limited by a stop 42b. It is highly desirable that the contacts 46, 47, 50, 48, 49 etc., are supported upon an insulating 65 panel immersed in oil and the whole trans-

former unit of which the unit 42 is the auxiliary secondary winding may be immersed in oil in a suitable container. In certain cases where convenient the unit 42 is not directly coupled to the primary winding 40 70 but is connected across an auxiliary secondary winding which is coupled to the primary 40 in order that the current through the unit 42 may be properly limited. A resistance or other type of current limiting device, such as a choke coil or a condenser 75 may be connected across the unit 42 instead of directly short circuiting it and if desired these current limiting devices may be made variable.

The auxiliary secondary winding 42 may be inductively coupled with primary winding 40 directly over secondary winding 39 or the auxiliary winding 42 may be disposed in axial alignment with primary winding 40 at 80 one end thereof. Where desired the auxiliary secondary winding 42 may be disposed on one leg of an iron core on interconnected legs of which the primary winding 40 and secondary winding 39 may be mounted. As 85 heretofore pointed out any form of load circuit may be employed with the transformer system of my invention and the glow discharge tube circuit is merely to be considered 90 in the illustrative sense.

It will be observed that various modifications of this invention may be made without departing from the spirit and scope thereof and that, therefore, I do not desire to limit this invention to the exact details as set forth 95 in the foregoing specification except in so far as they are defined by the appended claims.

What I claim as new and desire to secure by Letters Patent of the United States is as follows:

1. A transformer comprising a primary winding, a thermally responsive secondary winding associated therewith, a tapped secondary winding coupled with said primary winding and a switching device carried by a portion of said thermally responsive secondary winding and adapted to be shifted in position according to the expansion of said thermally responsive secondary winding depending upon the amplitude of current induced therein from said primary for establishing connection with selected taps on the aforesaid tapped secondary winding.

2. A transformer comprising a primary winding, a tapped secondary winding inductively related thereto, an inductively associated thermally responsive secondary winding, means interconnecting the ends of the thermally responsive secondary winding for forming a closed path therethrough, and a switching device operative upon the expansion of said secondary winding under the control of current induced therein from said primary winding for selecting a predetermined portion of said tapped secondary

winding for operation with a load circuit.

3. In a transformer system, a primary and secondary winding, a source of energy connected with said primary winding, a load circuit, tapped connections on said secondary winding leading to said load circuit, sets of contacts disposed in each of said tapped connections, an auxiliary secondary winding constituted by a thermally responsive strip member inductively associated with said primary winding and having the ends thereof connected through a shunt path, an insulated arm carried by said thermally responsive strip, a contact member supported by said insulated arm and adapted to bridge the individual sets of contacts for successively establishing circuits from the tapped connections on said secondary winding to said load circuit and means actuated by said thermally responsive strip member at the limit of movement thereof for interrupting the circuit between the source of energy and the primary winding for restoring said thermally responsive strip to the initial position thereof.
4. A transformer system comprising a source of potential, a primary winding connected with said source of potential, a pair of secondary windings inductively related to said primary winding, a load circuit, tapped connections for delivering different potentials from one of said secondary windings to said load circuit, a pair of contacts forming an open gap in each of said tapped connections, the other of said secondary windings comprising a thermally responsive strip inductively related to said primary winding with a shunt path connected across the terminals thereof, a contact member, means operable according to the thermal action upon said thermally responsive strip to cause said contact member to successively bridge each of the sets of contacts in said tapped connections for successively delivering different potentials to the load circuit according to the thermal action of said thermally responsive strip and means actuated by the movement of said thermally responsive strip to one of its limiting positions for interrupting the circuit between said source and said primary winding for permitting said thermally responsive strip to be restored to the initial position thereof.

5. A transformer system comprising a source of potential, a primary winding connected with said source of potential, a pair of secondary windings inductively related to said primary winding, a load circuit, tapped connections for delivering different potentials from one of said secondary windings to said load circuit, a pair of contacts forming an open gap in each of said tapped connections, the other of said secondary windings comprising a thermally responsive strip inductively related to said primary winding with a shunt path connected across

the terminals thereof, a contact member, means operable according to the thermal action upon said thermally responsive strip to cause said contact member to successively bridge each of the sets of contacts in said tapped connections for successively delivering different potentials to the load circuit according to the thermal action of said thermally responsive strip and time delay means actuated by said thermally responsive strip upon movement thereof to one of its expanded positions for interrupting the circuit between said source and said primary winding for a time interval sufficient to permit said thermally responsive strip to be restored to contracted position.

6. A transformer system comprising a source of potential, a primary winding connected with said source of potential, a pair of secondary windings inductively related to said primary winding, a load circuit, tapped connections for delivering different potentials from one of said secondary windings to said load circuit, a pair of contacts forming an open gap in each of said tapped connections, the other of said secondary windings comprising a thermally responsive strip inductively related to said primary winding with a shunt path connected across the terminals thereof, an insulated arm carried by said thermally responsive strip, a contact member mounted on said arm, means operable according to the thermal action upon said thermally responsive strip to cause said contact member to successively bridge each of the sets of contacts in said tapped connections for successively delivering different potentials to the load circuit according to the thermal action of said thermally responsive strip and a relay device having relatively large time constant and operated by movement of said thermally responsive strip to its expanded position for interrupting the circuit from said source to said primary winding for a time period sufficient to allow said contact member to pass over said contacts while said primary winding is de-energized to an initial position preparatory for a repeat operation when said primary winding is deenergized by operation of said time delay relay device.

7. In a transformer system for feeding a load circuit, the combination of a primary winding and a pair of secondary windings electromagnetically coupled with said primary winding, one of said secondary windings comprising a convolute bimetallic strip, a switch arm carried by the end of said bimetallic strip and a multiplicity of contacts connected with certain of the taps on the other of said secondary windings, said switch arm operating to connect selected portions of the tapped secondary winding to the load circuit according to the expansive and contrac-

tive action of said bimetallic secondary winding.

8. A transformer system for feeding a load circuit, comprising a primary winding and a pair of secondary windings inductively associated with said primary winding, one of said secondary windings being constituted by a thermally responsive strip member adapted to change in physical position according to the amplitude of current induced therein from said primary winding, a switch arm carried by said thermally responsive strip, contacts connected through taps with selected points on the other of said secondary windings, and connections to the load circuit controlled by the movement of said switch arm over said contacts to a position wherein said primary winding is automatically deenergized.

20 In testimony whereof I affix my signature.
BEN J. CHROMY.
